UNITED STATES PATENT OFFICE.

JOHN W. STEVENS, OF ST. PAUL, MINNESOTA.

CARBURETER.

1,184,889.

Specification of Letters Patent.

Patented May 30, 1916.

Application filed December 19, 1914. Serial No. 878,164.

To all whom it may concern:

Be it known that I, JOHN W. STEVENS, a citizen of the United States, resident of St. Paul, in the county of Ramsey and State of Minnesota, have invented certain new and useful Improvements in Carbureters, of which the following is a specification.

The object of my invention is to provide a carbureter in which the suction ports through which the mixture passes to the cylinders can be increased in effective area for increased speed of the engine, and the auxiliary or variable air ports also increased, but in less proportion or ratio to provide for increased suction at the nozzle.

Other objects of the invention will appear from the following detailed description.

The invention consists generally in various constructions and combinations, all as hereinafter described and particularly pointed out in the claims.

In the accompanying drawings forming part of this specification, Figure 1 is a vertical sectional view of a carbureter embodying my invention, Fig. 2 is a detail view of the cylinder throttle valve, Fig. 3 is a sectional view on the line $x-x$ of Fig. 1, Fig. 4 is a sectional view on the line $y-y$ of Fig. 1, Fig. 5 is a detail view, partially in section, of a modified construction.

In the drawing, 2 represents a casing having a fuel chamber or reservoir 3 communicating through a passage 4 and a valve 5 with a source of fuel supply, not shown. The movement of the valve is controlled by the usual float 6, which encircles an inner casing or shell 7 between which and the walls of the casing 2 the reservoir is formed. The casing 2 has a removable top 8 to allow access to a chamber 9 within the casing 7 through the open top 10 of said chamber. From this chamber a passage 11 leads to the engine cylinder, (not shown). In the base of the casing 7 is a hydro-carbon fuel duct 12 communicating with the chamber 3, and with a nozzle 13 which projects up into the chamber 9 and is provided with a needle valve 14 by means of which the flow of fuel through the nozzle is controlled in the usual way.

Within the casing 7 I provide a cylindrical member 15 having an annular flange 16 that is seated in the wall of the casing 7 near the middle portion thereof and separates the lower portion of this chamber from the upper portion. This member 15 is pro-

vided below said flange with variable air intake ports 17 extending vertically therein at intervals and spaced apart and communicating with the lower portion of the chamber 9 and with the open air through the passage 18 across which the duct 12 extends. Above the flange 16 suction ports 19 are formed in said cylindrical member. These ports 17 and 19 have preferably parallel vertical edges and converging end edges, so that the openings gradually increase in area from one longitudinal edge toward the opposite edge and the ports are oppositely arranged; that is, the ends converge in one direction in the upper group of ports and in the opposite direction in the lower group of ports, and as the openings in the upper ports increase in effective area through the movement of the throttle, the ports in the lower group will also increase, but in less proportion.

Fitting within the cylinder 15 is a hollow, member 20 substantially in the form of a truncated cone having a flange 21 seated against the lower end of the cylinder 15, the fuel supply nozzle 13 projecting upwardly into said member and terminating beneath and near fixed air intake ports 22 provided in the upper portion of said member. The cylinder 15 and the member 20 are normally stationary, and the ports 22 admit the gas mixture to the space within the cylinder 15. Within this cylinder 15 I provide a throttle valve 23, cylindrical in form, seated at its lower end on the flange 21 and having ports 24 above the flange 16, and similar ports 25 below the flange 16, adapted to register respectively with the ports 19 and 17 in the stationary cylinder. The valve 23 has a stem 26 provided with a lever 27 that is actuated by an arm 28 on a rock shaft 29 that is operated through a suitable mechanism extending to the driver's seat. The cylinder 23 constitutes, in effect, the throttle of the engine for by rotating it the driver can increase or decrease the area of the air ports in the cylinder 15 according to atmospheric conditions or the load on the engine. A stop pin 30 may be provided on the inner cylinder adapted to enter a notch 31 in the cylinder 15, and limit the rotating movement of the inner cylinder. The suction ports 19 will be partially open even when the throttle is rotated to entirely close the air ports 17, and, owing to the difference in shape of these ports, the movement of the

throttle in one direction to increase the area of the suction ports will, while increasing the width of the opening in the air ports 17, at the same time reduce their length and the proportion of increase in area in the ports 5 17 will therefore be less than in the suction ports and the vacuum around the nozzle will be increased and the feed of the fuel quickened. I am thus able to enlarge the 10 suction ports at will and increase the vacuum around the nozzle without at the same time introducing a proportionately greater volume of air through the auxiliary or variable intake ports. Generally in carbureters 15 the increase in speed to increase the suction will open the auxiliary valve and admit a correspondingly greater volume of air, which has the effect of reducing the vacuum at the nozzle, but in my improvement this 20 objection is avoided, as the movement of the throttle to increase the effective area of the suction ports through which the mixture is delivered to the cylinder, while opening the auxiliary ports, will do so in a lesser degree 25 than the suction ports and the vacuum around the nozzle will be increased instead of reduced.

In Fig. 5 I have shown a modified construction in which an outer cylinder 32 is 30 provided having ports 33 and 34 therein corresponding substantially to the ports 17 and 19, except that they are horizontally instead of vertically arranged in the cylinders. Both are tapered from one end to 35 toward the other, the taper of one group of ports being the reverse of the taper of the other group. Within this cylinder is a sliding throttle 35 having rectangular ports 36 therein adapted to register respectively with 40 the ports 33 and 34 and movable vertically in the cylinder instead of in a rotary direction. The function of this inner cylinder is substantially the same as the one described in reference to Fig. 1. The inner 45 cylinder will have a suitable link connection 37 with a suitable operating means, (not shown).

I claim as my invention:

1. A carbureter comprising a casing, a 50 sleeve arranged within said casing and having an annular flange that is seated against the walls of said casing dividing the space therein into an upper and a lower chamber, said sleeve having a group of ports in 55 its upper portion above said flange and a similar group in its lower portion below said flange, said ports having tapered walls and decreasing in area from one side toward the other, the taper of the upper group of ports 60 being oppositely arranged from that of the lower group of ports, a throttle valve for closing said ports, the movement of said valve in one direction increasing the length of the upper ports and correspondingly decreasing the length of the lower ports, a cone 65

shaped member projecting into the lower portion of said sleeve and having a series of fixed ports therein, the chamber below said flange communicating with the ports of said cone shaped member and with the lower 70 group of ports in said sleeve, and with an air intake, and a fuel supply nozzle projecting into said cone shaped member.

2. A carbureter comprising a casing having an air intake opening and a passage for 75 communication with the engine cylinders, a sleeve mounted in said casing and having ports in its lower portion communicating with said air intake passage and ports in its upper portion communicating with the passage to the engine cylinders, said ports having tapered walls, those of one group being oppositely arranged with respect to those of the other group, a throttle valve mounted for rotation in said sleeve and having groups 80 of ports arranged to register respectively with the groups of ports of said sleeve, the oppositely arranged taper of said sleeve ports providing for an increase in area of one group of sleeve ports and an increase in 85 area of the other group of ports, but in a different ratio, a cone shaped member having ports therein fitting within said sleeve and communicating with said air intake passage, and a fuel supply nozzle projecting 90 into said cone shaped member adjacent to the fixed ports therein.

3. A carbureter comprising a casing having inlet and outlet openings and a nozzle projecting through said inlet opening, concentric, relatively-movable members mounted within said casing and having upper and lower groups of ports opened and closed by the movement of one of said members, one of said members having an opening therein 100 to receive said nozzle and a member encircling said nozzle and provided with ports, the movement of one of said concentric members in one direction increasing the area of 105 the upper and lower groups of ports but increasing the area of the lower group in less proportion.

4. A carbureter comprising a casing having a chamber formed therein provided with inlet and outlet openings and a fuel supply 115 nozzle projecting into said chamber through said inlet opening, cylindrical members concentrically mounted within said chamber and relatively movable and one of them forming a throttle, means separating the 120 space in said chamber around the lower portion of said cylinders from the space in said chamber around the upper portion of said cylinders, one of said cylinders having a central opening into which said nozzle projects and a member encircling said nozzle, the upper portion of the walls of said encircling member having a series of ports therein, the ports in the upper portion of said cylindrical members communicating with the 125 130

upper part of said chamber and the ports in the lower walls of said cylindrical member communicating with the lower part of said chamber, the upper group of ports in 5 one member increasing in effective area with the movement of the throttle in one direction and the other group of ports also increasing in area with the movement of said

throttle but in less proportion, thereby increasing the suction at the nozzle.

In witness whereof I have hereunto set my hand this 14th day of December, 1914.

JOHN W. STEVENS.
